(21) Appl. No.: **29/504,849***Primary Examiner* — Michael A Pratt(22) Filed: **Oct. 9, 2014**(74) *Attorney, Agent, or Firm* — Patterson Intellectual Property Law; Ryan D. Levy(51) **LOC (10) Cl.** 22-01
 (52) **U.S. Cl.** USPC ..... **D22/108****CLAIM**(58) **Field of Classification Search**

What is claimed is the ornamental design for a bipod, as shown and described.

USPC D22/108
 CPC F41A 23/10; F41A 23/08; F41A 23/04
 See application file for complete search history.**DESCRIPTION**(56) **References Cited**

FIG. 1 is a bottom perspective view showing the bipod of Applicant's invention.

U.S. PATENT DOCUMENTS

FIG. 2 is a top perspective view of the bipod of Applicant's invention.

FIG. 3 is a top view of the bipod of Applicant's invention.

FIG. 4 is a bottom view of the bipod of Applicant's invention.

FIG. 5 is a side view of the bipod of Applicant's invention.

FIG. 6 is a side view of the bipod of Applicant's invention.

FIG. 7 is a bottom view of the bipod of Applicant's invention.

FIG. 8 is a top view of the bipod of Applicant's invention; and,

FIG. 9 is a view of the bipod of Applicant's invention with a firearm.

The dash-dot-dash lines shown in the Figures represent some embodiments of environmental structure and form no part of the claimed design. The dotted lines represent a firearm.
